UNITED STATES PATENT OFFICE.

THOMAS McDONNELL, JR., OF COCKEYSVILLE, MARYLAND.

STONE-CHANNELING MACHINE.

SPECIFICATION forming part of Letters Patent No. 391,260, dated October 16, 1888.

Application filed April 23, 1888. Serial No. 271,591. (No model.)

To all whom it may concern:

Be it known that I, THOMAS McDONNELL, Jr., a citizen of the United States, residing at Cockeysville, in the county of Baltimore and State 5 of Maryland, have invented certain new and useful Improvements in Stone-Channeling Machines; and I do hereby declare the following to be a full, clear, and exact description of the invention, such as will enable others skilled in the art to which it appertains to make and use the same.

My invention relates to a new and useful improvement in stone-channeling machines; and it consists in the construction and arrangement of parts, more fully hereinafter described, 15 and pointed out in the claims.

The object of my invention is to provide a stone channeling machine which shall be constructed in such a manner as to prevent the 20 action of the drills from jarring the frame and drill-operating portion of the machinery, thereby preventing damage, and still allow the same to be positive and effective in their working.

25 A further object consists in the arrangement of the drill-lifting mechanism in such a manner as to prevent the wrenching or breakage of the machine or drills when the latter become so wedged in the channel that the machine is 30 unable to extract the same without damage ensuing.

35 A further object consists in providing a stone-channeling machine of the kind herein-after described with suitable machinery whereby the drills may be removed after the completion of the work or placed into position when the same is commenced.

These objects are obtained by the construction 40 illustrated in the accompanying drawings, wherein like letters of reference indicate corresponding parts in the several views, and in which—

Figure 1 is a front elevation of my improved machine. Fig. 2 is a side elevation of the 45 same. Fig. 3 is an enlarged detail view of the lifting mechanism; Fig. 4, a detail view showing the inner serrated face of one of the retaining-clamps; and Fig. 5 is a modification of the lifting mechanism.

50 In the drawings, A represents the frame, provided on its under side with suitable trucks, a a, constructed to run upon tracks, (not

shown,) to allow of the frame being moved forward or backward, as necessity may require. Upon the upper side of said frame is provided 55 supports a a', which have suitable bearings formed in their upper ends, in which the horizontal crank-shaft B works.

C C indicate the vertical standard-guides, the lower ends thereof being bent in and secured to the frame at a point adjacent to the supports a a'. The upper ends of said guides are connected by a brace-bar, C'. On the vertical guides C C are placed sliding blocks D and D', the latter being of greater width than 60 the former and located beneath the same. Said blocks traverse the front of the vertical guides and have recesses d' d' formed in their outer faces of a depth equal to the thickness of the drills E. The width of these is sufficient to permit a gang of drills to be placed therein and a tightening or binding wedge, d', to be inserted between the sides of the last 65 drill and the flange formed by the edge of the block.

The construction of the clamping-blocks D and D' and the arrangement and construction of the drills in said blocks are more fully illustrated in Fig. 3 of the drawings, in which the 70 drills are shown as clamped and held in position within said blocks. To retain the drills 75 in their adjusted position and to prevent vertical movement of the same, I form upon the outer faces thereof, above the blades or points,

a series of inclined or diagonally-arranged serrations or ridges, which mesh or interlock with corresponding serrations formed in the inner faces of the clamping-plates F' F', so that the latter, when bolted or secured to the blocks, will be closely interlocked with the serrations of 80 the drills, thereby tightly packing the same within the blocks. It will be observed that as the impact of the drills, when the machine is 85 in operation, has a tendency to cause the vertical movement of the clamps, as well as to loosen the 90 drills from their adjusted position, I am, by providing the outer faces of the drills and inner faces of the clamping-plates with inclined serrations, enabled to overcome this defect, for the inclined serrations, instead of allowing a vertical 95 movement of the drills, force the same against the sides of the sliding blocks, and thus bind the same in place, at the same time relieving the clamping-plates from a great amount of 100

strain which they otherwise would be subjected to. It is therefore obvious that the greater the impact of the drills when the same, together with the clamping-plates, are provided with inclined serrations the tighter will be the binding thereof.

I am aware that it is not broadly new to provide the clamping-plates and drills with serrations for the purpose of enabling the same to mesh with one another, for this is shown in Patents Nos. 40,584 and 105,391; but the difference between these and my clamping-plate is in the construction of the same. In the above patents the serrations are horizontal, which makes the same subject to the defects hereinbefore described, and which the plates herein shown are designed to obviate, while I provide the drills and clamping-plates with diagonal serrations for the purposes above 20 stated.

I do not claim, broadly, clamping-plates provided with serrations meshing with like serrations formed upon the drills, but with diagonal serrations meshing with similar ones formed 25 upon the drills.

In machines of this class it is usual to allow the weight of the drills and clamping-blocks to give the necessary downward force to the drills. While this would answer, provided the 30 stone to be worked was directly beneath the machine, it would fail if it should become necessary to channel at an angle. To overcome this latter objection, as well as to add greater cutting force to the drills when in an upright 35 position, I preferably secure spiral springs *e* to the upper ends of the lower blocks, *D'*, and the upper ends I connect to the blocks *o'*, which blocks have recesses formed in their top in which the rods *o* fit. These rods have their 40 upper portion screw-threaded and are screwed into the blocks *o'*, connected to the inner face of the standard-guides. I am enabled by the screwing or unscrewing of this rod to tighten or loosen the springs *e*, thereby increasing or 45 decreasing the downward impetus of the drills. When the drills are raised, the springs will be compressed, and when released from their elevated position the springs will greatly add to their downward impetus. To raise the drills, 50 I employ a horizontal crank-shaft, *B*, above referred to, which is rotated by having direct communication with the piston of the engine, which is preferably located on the rear part of the frame, and which, forming no part of 55 my invention, need not herein be described, merely mentioning the fact that I employ the same to give forward or backward movement to the trucks above referred to, as well as to work the horizontal shaft. The ends of the 60 horizontal shaft have rigidly secured thereon circular disks *B'*, which have wrist-pins *b* placed eccentrically thereon. Journaled on the wrist-pins *b* are square head-blocks *G*, having a slot formed vertically therethrough, in 65 which are placed and operated pitmen *H*, pivotally connected to the sides of the blocks *D'*. The upper or protruding ends of the pit-

men *H* have removable caps *h* thereon, against which the upper ends of the spiral cushion-springs *J*, surrounding the upper ends of the pitmen, impinge, their lower ends resting on the top of the blocks *G'*. The pitmen *H* are of sufficient height to allow of a complete revolution of the disk *B'* without raising the drills; but by the interposition of the springs *J*, which have the required resiliency to withstand the weight of the drills without compression, or with very little, the said drills are raised as the head-blocks are carried up by the wrist-pins during the revolution of the disks. The downward movement of the drills is caused by the relaxation of the springs *e*, together with the weight of the blocks and drills. Of course the springs *J* are heavier than the springs *e*, so as to allow the latter to be compressed, while the former is very little compressed, if at all. The springs *J'*, situated below the block *G'*, surrounding the pitman, and having their lower ends resting upon the collar formed upon the pitman, serve to relieve the frame and engine from the jarring occasioned by the operation of the drills.

In Fig. 5 I have illustrated a modified form of my improved drill-lifting mechanism, which consists in securing to a plate, *p*, formed upon the standard-guides, the upper ends of spiral springs *n' n'*, their lower ends being connected to the block *D'*. When this form of connection is desired, the pitmen *H* are dispensed with, as well as all parts connected therewith, and motion is given to the drills by bringing the wrist-pins formed upon the disk in direct contact with the under face of the blocks *D'*; but I prefer to use the connection previously described, as I believe the same to be more effective in its operation.

I have shown in Fig. 1 of the drawings the brace-bar *C'* provided at or about midway between the two standard-guides with a swinging crane secured thereto. The standard portion of said crane is made hollow and provided upon its top with a pulley, *l'*, and upon the upper face of the extended arm thereof with pulley *l*. The object of this crane is to allow of quickly removing the drills from their position upon the completion of the work or to place the same in position upon commencement thereof, as the same are too heavy to permit of their handling by the workmen. To accomplish either of these objects, the crane is swung around until the pulley *l* hangs over the gang of drills. A rope, chain, or cable is then secured at some point to the drills, and then passes over the pulley *l* and pulley *l'*, down through the hollow standard portion of the crane, through an aperture formed in the brace-bar, and is then secured to a drum situated below the frame, which drum may either be turned by the engine or by hand. Upon the removal of one gang of drills the crane may be swung over to the other side, so as to permit the removal of the other gang.

The operation of my machine is as follows: As the shaft *B* is rotated by the piston of the

engine, the disks B' are revolved, which, as the 5
wrist-pins are placed eccentrically thereon and
secured to the head-blocks G, necessarily raises
the same, which in turn raises the drills through
the pitman H, attached to the clamp-blocks D'.
As the disks continue to revolve, the head- 10
blocks are lowered and the drills forced into
their work by gravity, the action of the springs
e and the downward movement of the wrist-
pins thus forming a positive action for the
drills. Should the drills at any time become 15
clogged or wedged in the channels, the sud-
den stoppage of the same would prevent the
revolution of the shaft B and great damage
ensue by breakage either to the drills, connec-
tions, shafts, or engine. To overcome this de- 20
fect, I provide, as previously stated, the springs
J, which are of sufficient strength to raise the
drills without compression or very slight com-
pression; but on the occurrence of the wedg-
ing of the drills they will be brought into use 25
and allow the machinery still to continue work-
ing, without damage being done to the drills
or other portion of the machinery, also allow-
ing a gang of drills so wedged to remain non-
working until relieved, while the other set still 30
continues its work.

It is obvious that many minor changes may
be made in the construction and arrangement
35 of the parts of my improved machine without
departing from the nature and principle of my
invention.

Having thus fully described my invention,
what I claim as new, and desire to secure by
Letters Patent of the United States, is—

1. In a stone channeling machine, the com-
bination, with the frame and the standard-
guides, of the crank-shaft having disks there-
on, wrist-pins eccentrically arranged upon said
40 disks, head-blocks connected to said wrist-
pins, pitmen sliding within the head-blocks,
and drills, substantially as herein shown and
described.

2. In a stone-channeling machine, the com-
bination, with the horizontal shaft having
45 disks upon the outer ends thereof, wrist-pins
formed upon said disks, of the head-blocks en-
gaging with said wrist-pins and having slots
therein through which the pitmen work, and
50 the sliding blocks for raising and lowering the
drills, substantially as herein shown and de-
scribed.

3. In a stone-channeling machine of the kind
herein shown and described, the combination,
55 with the engine, piston, shaft, disks having

wrist-pins formed thereon, and the head-blocks
working upon said wrist-pins, of the pitmen
having movable collars upon their upper ends
and lower portions thereof, and spiral springs
interposed on the pitmen between said collars 60
and the head-blocks in connection with the
sliding blocks, substantially as and for the pur-
pose set forth.

4. In a stone-channeling machine, the com-
bination, with the drill-clamps and the disks,
65 of the head-blocks mounted on said disks, the
pitmen working in said head-blocks, and spiral
springs arranged on the pitmen above and be-
low the head-blocks, substantially as herein
shown and described. 70

5. In a stone channeling machine, in combi-
nation with the drill-lifting mechanism, the
sliding blocks D' and D, having their outer
faces recessed to receive a gang of drills, the
drills having diagonal serrations on their 75
outer faces, and the drill-clamping plates hav-
ing inner diagonal serrations meshing with the
serrations on the drills, thereby holding the
latter in a rigid position, said clamping-plates
being bolted to the sliding blocks, substan- 80
tially as herein shown and described.

6. In a stone-channeling machine, the combi-
nation, with the lifting mechanism herein de-
scribed, of the means for adding impetus to
the downward movement of the drills, consist- 85
ing of the springs e, connected at their lower
ends with the head-blocks D' and at their up-
per ends with the blocks o', in connection with
the retaining-rod o, substantially as and for
the purpose set forth. 90

7. In a stone-channeling machine, the com-
bination, with the machinery herein described,
of the screw-threaded rod o, working in the
block o'', standard-guides C, recessed blocks o',
springs e, sliding blocks D', and drills, as and 95
for the purpose herein set forth.

8. In a stone-channeling machine, the com-
bination of the frame A, shaft B, having disks
B', the wrist-pins b, eccentrically secured on
said disks, the head-blocks G, pitmen H, 100
sliding clamps D and D', drills supported in
said clamps, the springs J, J', and e, and the
standard-guides, substantially as herein shown,
and for the purpose described.

In testimony whereof I affix my signature in 105
presence of two witnesses.

THOS. McDONNELL, JR.
